E. M. CLARK.
SCAFFOLDING BRACKET.
APPLICATION FILED MAR. 18, 1912.

Patented Oct. 21, 1913.

UNITED STATES PATENT OFFICE.

EDGAR M. CLARK, OF DAYTON, OHIO.

SCAFFOLDING-BRACKET.

1,076,270.

Specification of Letters Patent.

Patented Oct. 21, 1913.

Application filed March 18, 1912. Serial No. 684,377.

To all whom it may concern:

Be it known that I, EDGAR M. CLARK, a citizen of the United States, residing at Dayton, in the county of Montgomery and State of Ohio, have invented certain new and useful Improvements in Scaffolding-Brackets, of which the following is a specification, reference being had therein to the accompanying drawing.

16 This invention relates to scaffolding brackets and more particularly to a bracket of this kind adapted to be connected to the shingles of a roof.

15 The object of the invention is to provide a simple device of this character having a powerful grip on more than one shingle; further, to provide such a device having a plurality of gripping devices, all of which will be moved into operative engagement 20 with the shingles by the thrust of the scaffold; and further to provide such a device in which two gripping devices are so arranged that one will prevent the other from being moved over its center into an inoperative position.

25 In the accompanying drawings, Figure 1 is a perspective view of my invention showing the same applied to a roof; and Fig. 2 is a sectional view taken centrally through 30 the device and also showing the same applied to the shingles of a roof.

In these drawings I have illustrated one embodiment of my invention and have shown the same as comprising a base plate 35 1 adapted to be slipped beneath the lower edge of a shingle. Rigidly secured to the lower or rear edge of the base plate on each side thereof are upwardly and forwardly extending arms 2, the forward ends of which 40 project some distance beyond the lower end of the shingle when the device is in operative relation thereto.

45 Pivottally supported by the forward ends of the arms 2 is a clamping device which comprises a plate 3 having its lower edge serrated to form teeth 4 and provided with rearwardly extending arms 5 by means of which it is mounted on a shaft 6 which, in turn, is mounted in the arms 2. The plate 50 3 is preferably curved forwardly and upwardly so that its upper end 7 projects some distance beyond its lower end and will be engaged by the scantling or other timber comprising the scaffold. It will be noted that 55 the serrated edge of the plate 3 extends some

distance below its pivotal center. By moving the plate about its pivotal center this edge can be moved away from the base plate 1 to permit the latter to be placed beneath the shingle. When the base plate is in position with reference to the shingle the movement of the clamping plate 3 about the shaft 6 will cause the serrated edge thereof to engage the shingle and exert a gripping action thereon. The weight of the timber forming the scaffold will come against the upper edge of the clamping plate 7 and will tend to thrust the teeth farther into the shingle, thus increasing the gripping action of the device with the increase of the weight on the scaffold.

60 The clamping plate preferably has connected therewith a secondary gripping device which extends rearwardly and downwardly to grip the shingle upon which the base plate 1 rests. In the present form of the device the arms 5 by means of which the plate is mounted on the shaft 6 are extended rearwardly to a point beyond the rear end of the base plate and the rear ends 65 of these arms are curved downward and pointed to cause them to engage the shingle upon which the base plate rests when the clamping plate has been moved into operative engagement with the shingle beneath 70 which the base plate has been thrust. The thrust of the timber forming the scaffold against the upper edge of the clamping plate serves to thrust the points of the arms 5 into the roof as well as to thrust the serrated 75 edge of the plate into the roof. Moreover, these arms constitute guards which effectively prevent the thrust on the upper edge of the clamping plate from throwing the same over its pivotal center and thus moving 80 the serrated edge of that plate out of engagement with the shingle or loosening its grip on the shingle. These arms also form 85 actuating devices for the clamping plate which can be readily grasped to move the 90 clamping plate about its pivotal center.

95 The whole device is of a very simple character, can be built at low cost and is of a very strong durable character. Moreover, the device is provided with two gripping 100 devices, the gripping action of both of which is increased by any increased weight on the scaffold. The secondary gripping device constitutes a guard to prevent the overthrow 105 of the main gripping device and also serves 110

as an actuating device for the main clamping plate.

While I have shown and described one embodiment of my invention it will be understood that this has been chosen for the purposes of illustration only and that I do not desire to be limited to the details of construction shown and described, for obvious modifications will occur to a person skilled in the art.

Having thus fully described my invention, what I claim as new and desire to secure by Letters Patent, is:—

1. In a scaffold bracket, the combination, with a base-plate, of spaced brackets secured to said plate adjacent the side edges thereof, longitudinally disposed arms each fulcrumed adjacent one end upon a respective bracket, the longer end of each arm forming shingle-gripping means, and a transversely disposed plate rigidly connected to the shorter ends of the arms, and being disposed in an obtuse plane with respect to the plane of the base-plate whereby pressure exerted in one direction upon the upper portion thereof will cause the

longer ends of the arms to be forced downwardly.

2. In a scaffold bracket, the combination, with a base-plate, of spaced brackets secured to said plate adjacent the side edges thereof, longitudinally disposed arms each fulcrumed adjacent one end upon a respective bracket, the longer end of each arm forming shingle-gripping means, and a transversely disposed plate rigidly connected to the shorter ends of the arms, and disposed in an obtuse plane with respect to the plane of the base-plate whereby pressure exerted in one direction upon the upper portion thereof will cause the longer ends of the arms to be forced downwardly, said plate extending below the fulcrum of the arms and having its lower edge serrated to form a gripping element.

In testimony whereof, I affix my signature in presence of two witnesses.

EDGAR M. CLARK.

Witnesses:

HARRIET L. HAMMAKER,
L. W. JAMES.
